UNITED STATES PATENT OFFICE.

NORMAN K. WINSTON, OF NEW YORK, N. Y.

SHOE CONSTRUCTION.

Application filed February 19, 1921, Serial No. 446,320. Renewed June 27, 1925.

To all whom it may concern:

Be it known that NORMAN K. WINSTON, citizen of the United States, and resident of the city of New York, in the county of 5 New York and State of New York, has invented certain new and useful Improvements in Shoe Construction, of which the following is a specification.

This invention relates to shoes. One object thereof is to provide a shoe construction in which are provided means for reinforcing the lining of the quarters and adapted to serve also as a comfortable support for the arch of the foot.

Another object is to provide a shoe construction of the character described in which the quarter shall be made comparatively more durable at a comparatively low cost.

A further object is to provide a shoe construction with practical, simple, means for reinforcing the quarters and supporting the arch of the shoe when the shoe is laced about the wearer's foot, in a manner entailing comparatively small expense of material 25 and labor.

Other objects of this invention will be in part obvious and in part hereinafter pointed out.

The invention accordingly consists in the 30 features of construction, combinations of elements and arrangement of parts which will be exemplified in the construction hereinafter described and of which the scope of application will be indicated in the following claims.

In the accompanying drawings, in which is shown one of various possible illustrative embodiments of this invention,

Fig. 1 is a vertical elevation of a shoe 40 showing an embodiment of this invention with the quarter portion broken away so as to show the reinforcing and arch supporting means; and

Fig. 2 is an enlarged cross-sectional view 45 taken along line 2-2 of Fig. 1.

Referring in detail to the drawing, the invention is there shown as applied to an ordinary shoe such for example as the Goodyear welt type comprising the inner sole 10, the outer sole 11, the welt 12, the vamp 13, and the quarters 14, 15, the latter having the usual eyelet stays 16. The quarters 14, 15, each comprise the outer leather portion or upper 17 and the inner 50 fabric lining portion 18. Held between the outer leather portion 17 and the inner lin-

ing 18 is a reinforcing layer 19 of fabric such as heavy duck or canvas. This layer is of such width and is so located as to extend from the portion of the shoe corresponding to the metatarsal region of the 60 foot over the instep portion to the eyelet stays of the quarters. The portions 17, 18, and 19 may all be assembled and stitched together at the bottom by stitches 20 passing through the welt and the inner sole thus 65 securely fastening all of these parts together. Parallel rows of stitches 21 are also passed through the lining 18 and the reinforcing member 19 to securely hold the 70 latter in place. Thus, due to the securing of the inner portion of the reinforcing member 19 at the bottom thereof to the welt, lining and the outer leather portion and inner sole, when the shoe is laced up, the 75 reinforcing member necessarily tightens about the sides of the transverse arch or instep of the foot providing a comfortable support and comfortably sustaining the foot over where there is tendency to flat foot- 80 edness.

It will thus be seen that there is provided a shoe construction in which the several objects of this invention are achieved and which is well adapted to meet the 85 conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I 95 claim as new and desire to secure by Letters Patent:—

1. In a lace shoe, in combination with the inner sole and quarters having an upper leather portion and an inner lining, a reinforcing member comprising a continuous layer of fabric inserted between said outer portion and lining and extending from beneath the inner sole portion corresponding to the metatarsal region of the foot over the 100 instep up to the eyelet stays, said outer leather portions, reinforcing member and inner lining being secured at their bottom ends to the inner sole and welt, and at their upper ends between the eyelet stays, said 105 reinforcing members having parallel rows of stitching extending lengthwise thereof 110

from the bottom end to the upper end adjacent the eyelet stays for securing it to the lining.

2. A shoe embracing in its construction an upper, and its lining, and an interposed reinforcing member comprising a continuous layer of flexible material anchored at the shoe bottom together with the upper and lining, said member having its upper edge fastened at the eyelet stays over the instep portion of the shoe and firmly secured to the lining by parallel rows of stitching.

3. In a shoe having a bottom, an upper and a lining, reinforcing means comprising a continuous layer of fabric secured to the lining by a row of stitches and secured to the bottom on either side, and extending upward between the lining and the upper in a diagonal forward direction, the upper portion of said reinforcing means being fixedly secured to the eyelet stays.

4. In a shoe, the combination of the outer

portion or upper, the inside lining and a continuous layer of flexible reinforcing fabric secured to the lining by a row of 25 stitches and interposed between the lining and the outer cover and having its opposite ends securely fastened to the shoe.

5. In combination with a lace shoe having a bottom, an upper and a lining, a reinforcing member comprising a continuous layer of fabric extending from the portion corresponding to the metatarsal region of the foot and over the instep between the said upper and the lining, said member being secured by eyelets of the shoe to the upper adjacent to the edges of the vamp, the lower end of said member being anchored to the bottom of the shoe and the mid-section stitched to the said lining.

Signed at New York city, in the county of New York and State of New York, this 18th day of February A. D. 1921.

NORMAN K. WINSTON.
